ARTICLE RETAINER

Anthony J. Whittle, Chicago, Ill.

Application April 14, 1932, Serial No. 605,278

3 Claims. (Cl. 206—46)

My invention relates to devices for retaining articles in suspension and from falling or dropping away, and more particularly to such devices in this class which are adjustable for articles of different widths or thicknesses, and my main object is to provide a retainer of this kind which is self adjusting and readily yields to the application of the article.

A further object of the invention is to employ 10 a resilient member, such as a rubber band for the retaining unit.

A still further object of the invention is to design the novel retainer along lines of exceeding simplicity.

With the above objects in view and any others that may suggest themselves from the specification and claims to follow, a better understanding of the invention may be had by reference to the accompanying drawing, in which

20 Fig. 1 is a perspective view, showing one application of the novel retainer;

Fig. 2 is an elevation, partly broken away, showing the novel retainer employed for another use;

25 Fig. 3 is an edge view of the main portions of Fig. 2; and

Fig. 4 is a perspective view, partly in section, of a modification.

The articles for which the novel retainer is intended are of the elongated type, such as pencils, lollipop sticks, golf-tees and the like; and the principle I employ is to hold these articles to a support by means of the resilient member previously referred to, such member being self-adjustable to the thickness or width of the article.

35 For purposes of illustration, 10 denotes a display card or fixture intended to be hung on a wall or set on a counter. The card may serve for the display of a variety of pencils 11 and is 40 perforated with openings 10a which are large enough for the loose passage of any of the pencils. These may not only be of different diameters or girths but of various shapes, as clearly indicated in Fig. 1, and the openings 10a are made round 45 in order to facilitate the passage of the pencils in order to facilitate the passage of the pencils whatever their shapes may be.

With the pencils inserted as shown, it is apparent that they would readily tilt in the direction of their greater lengths and slide out of the 50 card 10 were not some means provided to retain them thereto. I provide this means in the form of an ordinary rubber band 12, which I pass longitudinally over the center of the card and also back of the same to seat in a convenient wall hook 55 13 and thus support the display. The band 12 is

applied before the pencils are inserted and placed so as to cross the line of openings 10a at substantially medial points. Thus, the insertion of each pencil will frictionally crowd the corresponding portion of the rubber band 12 in one or 60 the other direction, and when the pencil is released the friction of the band will retain it to the card. In order to assure the engagement of the band with each pencil of the series, the pencils are inserted on alternate sides of the band 65 as shown.

Figs. 2 and 3 show the application of the invention to a pill box type of golf-tee retainer 14. The box is made with a series of openings 14a in its periphery, these openings being sufficiently spacious to permit the insertion of the shank 15a of a variety of golf-tees 15, such shanks being of various diameters and shapes. The illustrations show that the rubber band 16 is wrapped over the periphery of the box, and that 70 the golf-tees are applied alternately in the same manner as the pencils in the form of Fig. 1, being thus retained to the box. For convenience, the box 14 is made with a staple fastener 17 which is attached to the side of a golf bag 18.

75 Fig. 4 illustrates a solid type of golf-tee retainer 19, preferably made of wood. In this modification, a series of spacious radial bores 19a is made to receive the tee-shanks 15a, and the bores are interconnected by a peripheral, medially-located groove 19b. The rubber band 16, somewhat tensioned, is seated in this groove. By medially intersecting the bore entrances, the rubber band presents a greater resistance to the insertion of the tees, being forced to arch laterally as indicated by dotted lines at the top of Fig. 4. The band therefore holds the tees more firmly and cannot creep laterally out of the zone of function or to slide off the retainer periphery.

80 It will be seen that the novel retainer not only holds the articles applied thereto irrespective as to their shape and girth, but also permits any of the articles to be withdrawn without difficulty. The retaining feature is but a simple, standard rubber band, and the accessory perforated card or holder is also an item of exceeding simplicity, making the device an inexpensive one to produce and a very easy one to handle and use.

I claim:

85 1. A retainer for golf tees comprising a solid disc, radial tee carrying recesses in the periphery of said disc, a surface groove in said periphery medially intersecting each of said recesses, and a rubber band removably carried by said groove and 90 extending across said recesses.

2. A retainer for golf tees comprising a solid disc, radial tee carrying recesses in the periphery of said disc, a surface groove in said periphery medially intersecting each of said recesses, and a 5 rubber band carried by said groove and extending across said recesses so that the insertion of a tee in a recess deflects said rubber band.

3. A retainer for golf tees comprising a solid

disc, radial tee carrying recesses in the periphery of said disc, a surface groove in said periphery medially intersecting each of said recesses, and a rubber band removably carried by said groove and extending across said recesses so that 80 the insertion of a tee in a recess deflects said rubber band.
